Primary Examiner — David Muller*(74) Attorney, Agent, or Firm* — Louis Woo(57) **CLAIM**

The ornamental design for a needle assembly, as shown and described.

DESCRIPTION

FIG. 1 is a top view of the needle assembly of the instant invention;

FIG. 2 is the bottom view of the needle assembly of the instant invention;

FIG. 3 is a side view of the needle assembly of the instant invention;

FIG. 4 is another side view of the needle assembly of the instant invention;

FIG. 5 is a rear view of the needle assembly of the instant invention;

FIG. 6 is a front view of the needle assembly of the instant invention;

FIG. 7 is a perspective view of the needle assembly viewed from front; and,

FIG. 8 is a perspective view of the needle assembly viewed from behind.

The dash dot line immediately adjacent to the claimed area in FIG. 5 represents the boundaries of the claimed design and does not form any part of the claimed design.
